(57) **CLAIM**

I claim the ornamental design for a fan bottle with sloped front, as shown and described.

DESCRIPTION

FIG. 1 is a top right front corner perspective view of the fan bottle with sloped front showing my new design;

FIG. 2 is a bottom right front corner perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top view thereof; and,

FIG. 8 is a bottom view thereof.

The broken lines in the drawings depict environmental subject matter only and form no part of the claimed design.
